UNITED STATES PATENT OFFICE.

WILLIAM KLOCKE, OF BROOKLYN, NEW YORK, ASSIGNOR TO E. W. BLISS COMPANY, OF BROOKLYN, NEW YORK, A CORPORATION OF WEST VIRGINIA.

PRESS.

No. 928,609.

Specification of Letters Patent.

Patented July 20, 1909.

Application filed April 1, 1908. Serial No. 424,631.

To all whom it may concern:

Be it known that I, WILLIAM KLOCKE, a citizen of the United States, residing in the borough of Brooklyn, county of Kings, city 5 and State of New York, have invented certain new and useful Improvements in Presses, of which the following is a specification.

This invention aims to provide certain improvements especially applicable to drawing presses for drawing large articles, such, for example, as bath tubs, and in which so long a stroke is necessary as to require a hydraulic ram. Such presses have a blank-holder consisting of two members between which the edge of the sheet to be drawn is clamped, and in some styles of press the upper member of the blank-holder is movable, in other styles the lower, and in still other styles both members.

This invention provides a very convenient means for applying to the operation of a movable member of a blank-holder the movement of the plunger which effects the drawing operation. In such machines it has been previously customary to provide separate hydraulic mechanism for operating the blank-holder, but by the introduction of this invention such separate hydraulic mechanism is entirely eliminated, and a great saving in initial cost and in expense of maintenance is provided.

Other features of improvement are referred to in detail hereinafter.

The accompanying drawings illustrate an embodiment of the invention.

Figure 1 is a side elevation of the machine. Figs. 2, 3 and 4 are face elevations showing the successive positions of the parts, 40 and showing the work in section. Fig. 5 is a section on the line 5—5 of Fig. 2. Fig. 6 is a half elevation and half section of the same.

Referring now to the embodiment of the invention illustrated, the blank-holder comprises a fixed lower member A and a movable upper member B. The movable member of the blank-holder, or, as it is generally called, the blank-holder, B, is mounted upon 50 a slide C which travels between the four uprights D constituting the main frame of the machine. The drawing punch E is mounted on a slide F working within the slide C and supported by rods G G' from a cross-head 55 H which is mounted upon the lower end of

the plunger J of the ram K, the latter being fixed in the head L of the machine frame, and the cross-head H being properly guided in the side frames D of the machine. The cross-head H is connected at opposite 60 ends with rods M which at their upper ends are connected with plungers N in supplementary cylinders O. There are two of these cylinders, one at each side of the machine, and liquid under pressure is constantly in 65 communication with the lower part of each cylinder so as to exert an upward effect upon the cross-head and punch, counterbalancing them. There is no valve mechanism nor anything except a counterbalancing effect in 70 these cylinders. The main cylinder or ram K may be provided with any usual or suitable connections for pressing down the plunger, the release of the pressure serving to permit the lifting of the plunger and connected parts by the counterbalancing cylinders. 75

Hydraulic mechanism is practically essential in machines designed for this class of work requiring a comparatively long and 80 uniform movement, and such machines are of great height (the present machine being more than 30 feet high). To convert the continuous long movement of the main plunger into a movement of a blank-holder at a 85 gradually decreasing speed until the blank is perfectly clamped, and to hold the blank-holder in this position while the punch draws the metal to the shape desired by the operation of the same main plunger, this invention provides a very simple and effective mechanism. 90 In the example shown the desired movement is effected through toggle links P and Q, each of which is operated by means of a link R fastened to the cross-head H which travels 95 up and down with the plunger J. In the highest position of the plunger (Fig. 4) the links R stand approximately in line with the links P, and the downward movement of the plunger is transmitted through the links P 100 to the slide C carrying the blank-holder at a comparatively rapid rate. As the links P and Q approach a position in line with each other (Fig. 3) the movement becomes more gradual and finally ceases, with the pressure 105 at a maximum, and the strain transmitted in a substantially straight line through the pins S, T and U to the side frame D of the machine. From the point at which the toggle links are substantially in line with each other 110

the further movement of the plunger effects simply a drawing movement of the punch E at the regular rate of speed desired.

In order to be able to remove the work from the machine the punch must start from a point well above the bed of the machine, and the initial movement of the punch to cover this distance is availed of according to this invention for the purpose of clamping the work in place. The work V (Fig. 2) is finished in an upright position and is raised to approximately the level of the fixed bed A by means of a knock-out plate W which is supported from a cross-beam X, preferably lying in a pit below the floor level, and which is connected by rods Y with the ends of the slide C which lies between the side frames D of the machine at the opposite sides of the machine. Thus on the return movement the punch is first withdrawn from the work and then the movable blank-holder is raised and with it the knock-out plate and the work.

I prefer to provide an adjustable connection of the slide C with the toggle links P, and for this purpose each of the pins S at the lower ends of the toggle links is mounted in a block Z which is adjustably fastened to the slide C by a mechanism illustrated in section in Fig. 5. The block Z is fastened down into the slide by means of bolts a and rests upon the inclined top of a wedge b, the bolts a passing through suitable slots in said wedge; and said wedge carries rotatably in its end a screw c which screws through a nut d fastened against the face of the main slide C, said screw c being provided with a capstan head e. By loosening the holding-down bolts a and screwing up the adjusting screw c, the pin S may be lifted, or, by the opposite operation, may be lowered, at will. The nut d is split, and is clamped by means of a screw f to hold the adjusting screw c firmly.

The broad idea of using a single ram to operate the punch and also the blank holder is not claimed in the present application, being covered by my prior application No. 389,574, filed August 21, 1907.

What I claim is:

1. A drawing press including a punch and a movable member of a blank-holder, both adapted to move in the same direction in drawing an article, and a single ram operating said punch and said movable member.

2. A drawing press including a punch operating from above and an upper movable member of a blank-holder, and a single hydraulic ram operating both said punch and said movable member.

3. A drawing press including a punch and a movable member of a blank-holder, a ram for operating said punch, and transmitting mechanism for communicating a part of the movement of said ram to said movable member, said ram and transmitting mechanism being both on the same side of the work.

4. A drawing press including two movable members, a hydraulic ram operating one of said members, a toggle mechanism having one toggle link connected to a fixed point and the other toggle link connected to the other of said movable members and having an operating link pivotally connected to said toggle links and to said ram. 70

5. A press for drawing large articles, including an upper punch, an upper movable member of the blank-holder, a hydraulic ram actuating said punch, toggle mechanism actuated by the first part of the movement of said ram and actuating said movable member of the blank-holder, and an ejector below the work and connected with said movable member to lift the drawn article as said movable member rises. 75 80

6. A drawing press including in combination a punch and a movable member of a blank holder, a ram having a plunger J actuating said punch, a pair of toggle links P and Q connected to said movable member and to a fixed point respectively and also connected to each other, and an operating link R connected to said ram and to said toggles to operate the latter. 85 90

7. A drawing press including in combination a punch and a movable member of a blank holder, a ram having a plunger J actuating said punch, a pair of toggle links P and Q connected to said movable member and to a fixed point respectively and also connected to each other, and an operating link R connected to said ram and to said toggles to operate the latter, the first part of the movement of said ram serving to move said toggle links from a bent to a straight position, and the continued movement of the ram serving to move its point of connection with said operating link R without material movement of the toggle links. 95 100 105

8. A press including in combination a movable member C, a link P through which movement is transmitted thereto, a block Z to which an end of said link is pivoted, and means for adjustably attaching said block Z to said member C. 110

9. A press including in combination a movable member C, a link P through which movement is transmitted thereto, a block Z to which an end of said link is pivoted, and means for adjustably attaching said block Z to said member C, said means including bolts a, a wedge b and a screw c, whereby said wedge may be shifted under the block Z to lift the latter to the limit allowed by the bolts a. 115 120

In witness whereof, I have hereunto signed my name in the presence of two subscribing 125 witnesses.

WILLIAM KLOCKE.
